UNITED STATES PATENT OFFICE.

JOHN W. HEATON, OF INDIANAPOLIS, INDIANA, ASSIGNOR OF THREE-FOURTHS TO CAROLINE A. HEATON, SAMUEL STEPHENS, AND ALEXANDER C. AYRES, OF SAME PLACE.

MACHINE FOR TONGUING AND GROOVING LUMBER.

SPECIFICATION forming part of Letters Patent No. 600,785, dated March 15, 1898.

Application filed April 6, 1897. Serial No. 630,910. (No model.)

To all whom it may concern:

Be it known that I, JOHN W. HEATON, a citizen of the United States, residing at Indianapolis, in the county of Marion and State of Indiana, have invented certain new and useful Improvements in Machines for Tonguing and Grooving Lumber, of which the following is a specification.

The object of my said invention is especially to produce a machine by which tongues and grooves can be successfully formed on very thin lumber; and it consists in certain details of construction and arrangements of parts in and about the cutter-heads of the machine, as will be hereinafter more particularly described and claimed.

Referring to the accompanying drawings, which are made a part hereof and on which similar letters and numerals of reference indicate similar parts, Figure 1 is a perspective view of the rear end of a suitable machine for the purpose provided with cutter-heads and bearings embodying my present invention; Fig. 2, a sectional view longitudinally of the machine alongside one of the cutter-heads and its spindle; Fig. 3, a sectional view taken transversely of the machine, showing the upper ends of both spindles and their cutter-heads, one being in section and the other in elevation; Fig. 4, a plan view of substantially the same parts shown in Fig. 3; and Figs. 5 and 6, views, on an enlarged scale, of lumber on which the tongues and grooves have been cut in my machine.

35 The machine as a whole may be briefly described as follows:

Two rods A' and A² are mounted in the frame A and carry the hangers B, in which the spindles C of the cutter-heads are mounted. The hangers develop into hollow blocks, which extend beneath the cutter-heads and serve to substantially fill the space which would otherwise exist in the machine-table. A screw-rod A³, also mounted in the frame 45 A, is used to adjust the hangers, and with them the spindles and cutter-heads, toward or from each other and give them the position desired.

The cutter-heads are composed of several 50 saws or toothed plates, as best shown in Figs.

2 and 3, two forms being shown, so that the particular form of structure best shown in Fig. 5 and for the making of which my machine is especially designed may be produced. Appropriate collars 5 and 6 are also preferably used to additionally steady the saws or plates in the center, and the whole are held together by screws or bolts 7. The central plates or saws are of the thickness which it is designed the grooves shall be. 55 60

My machine is especially designed to produce what is known as "parquetry" flooring or wood carpeting, which, as is well known, is very thin, and consequently it has been difficult to make an efficient and durable cutter-head, the groove-cutting portion of which should be sufficiently thin to cut the required groove and at the same time sufficiently strong and rigid and capable of the required adjustments. By using three toothed plates or saws 70 1, 2, and 3, as shown at the left in Fig. 3, the central one may be as thin as required and may be changed from time to time as it is desired to change the thickness, while the outer ones may be thick enough to firmly support 75 said inner one and at the same time do their share of the cutting. In the form shown at the right in Fig. 3 a cutter-head formed of four plates 1, 2, 3, and 4 is shown. This is for the purpose of forming a scarf on the under side at one edge of the lumber, as shown in Fig. 5, for the purpose of receiving the horizontal portions of certain anchors or fasteners which are the subject of another invention. As before, the inner saws are of exactly the thickness of cut desired, while the outer ones are thick enough to firmly support 80 the thin inner ones. These cutter-heads as a whole are mounted on screw-threaded portions of the spindle C, being held to the desired adjusted positions thereon by means of the lock-nuts n n' n² n³. By this means an extremely accurate adjustment of the cutter-heads is provided for without the necessity of disturbing the spindles in their bearings. 85 90 95

In fine small work, such as this machine is designed to operate upon, it is of great importance that exact accuracy of width shall be preserved and that there shall therefore be no tremble or swinging of the spindles. 100

I have therefore provided a bridge-tree D, which extends across the machine and in which are mounted bearings E, which carry the upper ends of the spindles. The bridge-tree, as best shown in Fig. 4, is slotted throughout its central portion, so that the bearings may be conveniently adjusted thereon, and said bearings, as best shown in Fig. 2, are clamped onto said bridge-tree by bolts e and clamp-bars E'. By loosening the nuts on these bolts e the bearings E can obviously be adjusted to any point desired and there firmly secured.

Having thus fully described my said invention, what I claim as new, and desire to secure by Letters Patent, is—

1. The combination, in a tonguing and grooving machine, of a suitable frame, rods extending across said frame beneath its table 20 one above the other, hangers each formed with connections by which they are mounted to slide on both of said rods, the upper ends of said hangers being developed into hollow blocks which extend up into an opening in 25 the table beneath the cutter-heads, means for adjusting said hangers on said rods, bearings formed in each of said hangers, spindles mounted in said bearings, cutter-heads mounted on said spindles, the upper ends of said

spindles being mounted in adjustable bearings on a bridge-tree above said cutter-heads, and means for securing and adjusting said parts, substantially as set forth. 30

2. The combination, in a machine for tonguing and grooving lumber, of the frame, the transversely-adjustable hangers formed with vertical bearings mounted in said frame, spindles with screw-threaded upper ends mounted in said bearings, cutter-heads consisting of saws or toothed plates of different diameters placed face to face and rigidly clamped and secured together the outside plates being of sufficient rigidity to support the inner thin plate, mounted on said screw-threaded ends by means of jam-nuts above and below them, a bridge-tree above said cutter-heads, bearings for the upper ends of said spindles mounted to be adjusted on said bridge-tree, and means for securing and adjusting said parts, all substantially as set forth. 40

In witness whereof I have hereunto set my hand and seal at Indianapolis, Indiana, this 3d day of April, A. D. 1897.

JOHN W. HEATON. [L. S.]
